Primary Examiner—Martie K. Holtje

(57) **CLAIM**

I claim the ornamental design for a conductor's illuminated baton, as shown and described.

DESCRIPTION

FIG. 1 is a front perspective view of a conductor's illuminated baton showing my new design;

FIG. 2 is a front elevational view;

FIG. 3 is a rear elevational view;

FIG. 4 is a right side elevational view;

FIG. 5 is a left side elevational view;

FIG. 6 is a bottom plan view; and,

FIG. 7 is a top plan view thereof.
